Specification of Letters Patent. Patented June 22, 1920.

Application filed June 9, 1919. Serial No. 302,861.

To all whom it may concern:

Be it known that we, CHARLES W. RIPSCH, JAMES C. DAWLEY, and CHARLES D. DERBY, citizens of the United States, residing at Dayton, in the county of Montgomery and State of Ohio, have invented certain new and useful Improvements in Lifting-Jacks, of which the following is a specification, reference being had therein to the accompanying drawing.

This invention relates to lifting jacks and more particularly to what is known as a self lowering jack.

The object of the invention is to provide a device of this kind having improved controlling means whereby the load, as it descends by gravity, will at all times be under the full control of the operator.

A further object of the invention is to provide a device of this kind in which the downward movement of the load will be retarded by the thrust, or frictional contact, of the controlling devices, which will absorb so large a part of the power exerted thereon by the load that little power will remain to be overcome by the braking device.

A further object of the invention is to provide a device of this kind which will be simple in its construction and operation, will comprise but a small number of parts, and will be of a very strong, durable character.

Other objects of the invention will appear as the mechanism is described in detail.

In the accompanying drawings Figure 1 is a side elevation of a lifting jack embodying our invention; Fig. 2 is a vertical section, with the lower part of the jack in elevation; Fig. 3 is a plan view of the jack partly in section, the section being taken on the line 3—3 of Fig. 2; Fig. 4 is a side elevation of the upper part of the jack with the end plate removed to show the braking devices in elevation; Fig. 5 is a sectional view taken on the line 5—5 of Fig. 2; and Fig. 6 is a sectional view taken on the line x—x of Fig. 4.

In these drawings we have illustrated one embodiment of our invention and have shown the same as applied to a lifting jack of the screw operated type. It will be understood, however, that the jack here shown has been chosen for the purpose of illustration only, and that the invention may be embodied in jacks of various kinds.

The jack here illustrated comprises a base 1, secured to which is an upwardly extending hollow standard 2 having mounted in the upper end thereof a nut 3, which, in the present construction, is formed separate from the standard and is held against rotation relatively to the standard by means of lugs 4 extending through recesses in the upper end of the standard. Mounted in the nut 3 and extending lengthwise of the standard is a screw 5 which constitutes the lifting element of the jack. Mounted on the upper end of this screw is a work engaging device or cap 6 upon which the load is supported. Secured to the cap 6 is a downwardly extending housing or sleeve 7 which incloses the standard 2 and engages the same to guide the work supporting cap 6 and maintain the same in proper alignment with the screw. The lugs 4 of the nut 3 extend outwardly beyond the standard 2 into the path 75 of the lower portion of the sleeve 7, which fits the standard snugly, and act as stops to limit the upward movement of the sleeve. Mounted on the screw 5 above the upper end of the standard 2 is a beveled gear 8 which is here shown as rigidly secured to a reduced upper end portion or pintle 9 of the screw. The beveled gear 8 meshes with a second beveled gear 10 mounted on the inner end of an operating shaft 11 which is journaled in a suitable bearing 12 formed in a plate 13 which closes an opening in the side wall of the housing 7. Secured to the plate 13 and extending laterally therefrom is a casing 14 having a transverse partition 15 in 90 which is formed a second bearing 16 for the operating shaft 11. The outer end of the casing 14 is closed by a removable cover or end plate 17. The end of the operating shaft 11 extends beyond the end plate 17 and has secured thereto a ratchet wheel 18 which is acted upon by a pawl 19 carried by a lever 20 pivotally mounted on the end of the shaft 11, to rotate the shaft, and through the medium of the beveled gears 10 and 8 to rotate the lifting screw 5. An anti-friction thrust bearing 21 is interposed between the beveled gear 8 and the load supporting cap 6 to permit the screw to rotate freely relatively to the load.

The pitch of the thread of the screw 5 is such that when unrestrained the screw will be rotated by the weight of the load and

permit the latter to move downward by gravity. It is necessary, however, that means be provided for controlling this downward movement of the load and, to accomplish this, we have provided controlling mechanism which will be automatically connected with the lifting element when the latter moves downwardly and will retard its downward movement. This retarding or power absorbing action will result from the end thrust or frictional contact of the controlling elements and, further, the controlling elements are of such a character that the power will be very largely absorbed by them and little remain to be absorbed or overcome by the braking devices. As here illustrated, the controlling devices comprise a worm wheel 22 loosely mounted on the operating shaft 11 and adapted to be connected thereto by a one way clutch, that is, a clutch which will connect the worm wheel with the shaft only when the latter rotates in one direction. As here shown, the worm wheel has secured thereto and forming, in effect, a part thereof, an annular series of clutch teeth 23 which coöperate with a similar series of clutch teeth on a movable clutch member 24 which is here shown as slidably mounted upon and held against rotation relatively to the operating shaft, preferably by mounting the same on a non-circular portion of the shaft, as shown at 25. The teeth of the two clutch members are so arranged that the worm wheel will be connected with the shaft only when the latter is rotated in a reverse direction, that is, when the lifting element moves downwardly. When the operating shaft is actuated to impart lifting movement to the lifting element, the teeth of the movable clutch member will ride over the teeth of that clutch member which is secured to the worm wheel without imparting movement thereto. Any suitable means may be provided for holding the movable clutch member yieldingly in engagement with the fixed clutch member and, in the present instance, we have employed a plurality of springs 26, one only of which is here shown, mounted in recesses in the partition 15 and provided with balls 27 which bear against the flange like outer portion of the clutch member 24.

The worm wheel 22 meshes with a worm 28 which is rigidly mounted on a shaft 29 carried by the side walls of the casing 14 and provided with an anti-friction thrust bearing 30. The teeth of the worm wheel 22 and the spiral of the worm 28 are set at such angles that the worm wheel will rotate the worm when downward movement is imparted to the lifting element or screw 5. This angle, however, is only slightly beyond the angle at which the worm would lock the worm wheel against rotation and, consequently, the worm will exert a very decided

retarding action upon the movement of the worm wheel and will absorb a great deal of the power applied to that wheel by the load on the lifting element. Mounted for rotation about the axis of the worm 28 and connected therewith is a second worm wheel 31 which, in the present instance, is mounted on the shaft 29 which carries the worm wheel 28 and has its hub provided with recesses 32 to receive tongues on the hub of the worm, and thus connect the worm wheel rigidly with the worm. The worm wheel 31 meshes with a second worm 33 which is secured to a shaft 34 extending at right angles to the worm shaft 29 and journaled in the plate 13 and partition 15 of the casing 14. This shaft also is provided with an anti-friction thrust bearing 35. The teeth of the worm 31 and the spiral of the worm 33 are set at such angles that the worm will be rotated by the worm wheel but will exert a retarding action on the movement of the worm wheel and will absorb a large part of the power applied thereto. Connected with the worm 33 are suitable braking devices which, as here shown, comprise a friction drum 36 rigidly secured to the shaft 34, between the partition 15 and the end plate 17. Coöperating with the friction drum 36 are two brake shoes 37 which are carried by intersecting arms 38 pivotally mounted on a stud 39 carried by the partition 15. The arms 38 project some distance beyond their axes 39 and are acted upon by a spring 40 which tends to move them toward each other and to thus cause the brake shoes 37 to frictionally engage the drum 36. This braking action is sufficient to overcome any power which may be applied to the brake drum through the worms and worm wheel, and will serve to lock the controlling mechanism against movement and thus hold the lifting element against downward movement. To permit the downward movement of the lifting element the controlling mechanism is released by moving the arms 38 away from each other, against the tension of the spring 40, and thus relieving the frictional contact between the brake shoes and the brake drum. This may be accomplished in various ways but, as here shown, I have interposed between the arms 38 a cam member 41 which, in the present instance, comprises the flattened end of a stud 42 which is rotatably mounted in the wall of the casing 14 and has secured to its outer end an actuating lever 43 by means of which it may be rotated and caused to spread the arms 38. The interior of the casing 14 forms a lubricant receptacle so that a part of the controlling mechanism may run in an oil bath and thus provide ample lubrication for all of the controlling mechanism. The casing also forms a dust proof housing for the mechanism.

The operation of the mechanism will be readily understood from the foregoing description thereof, and it will be apparent that when the load which has been elevated 5 is to be lowered this is accomplished automatically by merely manipulating the braking devices to release the controlling mechanism. When the controlling mechanism has been thus released, the rotation of the screw 10 5, which is brought about by the downward movement of the load, will impart rotatory movement to the shaft 11 in a reverse direction, thus causing this shaft to pick up, and impart rotatory movement to the worm 15 wheel 22. Because of the angles at which the teeth of the worm wheel and the spiral of the worm 28 are set, the worm wheel will impart rotatory movement to the worm, but, because of the angle at which the spiral is 20 set, the worm will impart a very decided retarding action to the rotation of the worm wheel, and will absorb much of the power thus applied thereto. This absorption of power is due to the thrust on the worm and 25 the frictional contact between the worm wheel and the worm. The braking devices serve to control the rotation of the worm and thus regulate the speed at which the load is lowered. In the present instance a second 30 worm wheel and worm are interposed between the first worm and the braking devices. The retarding and power absorbing action of the controlling mechanism does not in any way depend upon the inertia of 35 the mechanism, and in this way distinguishes from and is a marked improvement upon that type of controlling device in which an extended train of multiplying gearing is employed to transmit the power from the load 40 to the braking devices. With such a train of gearing, the retarding action is reduced as the train of gearing gains momentum, and the efficiency of the device is thus likewise reduced. With the present device the 45 parts of the controlling mechanism acquire no appreciable momentum and the thrust on the worms has a constant and effective retarding action upon the rotation of the operating shaft. It will also be noted that the 50 construction is of such a character that it requires the use of a very small number of parts, and that these parts are such that they may be made of a very strong durable 55 character.

While we have shown and described one embodiment of our invention, we wish it to be understood that we do not desire to be limited to the details of construction thereof, as various modifications may occur to a 60 person skilled in the art.

Having thus fully described our invention, what we claim as new and desire to secure by Letters Patent is:

1. In a lifting jack, a lifting member, a 65 shaft operatively connected with said lift-

ing member, a worm wheel mounted on said shaft and adapted to be rotated thereby when said shaft is rotated by the downward movement of said lifting member, a worm meshing with said worm wheel and having 70 its spiral so arranged that said worm will be rotated by said worm wheel, a second worm wheel connected with said worm for rotation therewith, a worm meshing with and adapted to be rotated by the last mentioned worm wheel, and a braking device connected with the last mentioned worm. 75

2. In a lifting jack, a lifting member, a shaft operatively connected with said lifting member, a worm wheel mounted on said shaft 80 and adapted to be rotated thereby when said shaft is rotated by the downward movement of said lifting member, a worm meshing with said worm wheel and having its spiral so arranged that said worm will be rotated by 85 said worm wheel, a shaft for said worm, a worm wheel mounted on said shaft and rigidly connected with said worm, a second worm meshing with and adapted to be rotated by the last mentioned worm wheel, a 90 braking device comprising a member rigidly connected with the last mentioned worm, friction devices coöperating with said braking member, and manually operated means to control said friction devices. 95

3. In a lifting jack, a lifting member, a worm wheel, means to connect said worm wheel with said lifting member when the latter moves downwardly, a worm meshing with and rotatable by said worm wheel, a 100 second worm wheel connected with said worm for rotation therewith, a second worm operatively connected with and rotatable by said second worm wheel, and a braking device connected with said second worm. 105

4. In a lifting jack, a lifting member, a worm wheel, means to connect said worm wheel with said lifting member when the latter moves downwardly, a worm meshing with said worm wheel and having its spiral 110 set at an angle just beyond the locking position, a worm wheel connected with said worm, for rotation about the axis thereof, a second worm meshing with and rotatable by said last mentioned worm wheel, and braking devices connected with the last mentioned worm. 115

5. In a lifting jack, a lifting member, an operating shaft connected with said lifting member, means for rotating said shaft to 120 impart lifting movement to said lifting member, a worm wheel loosely mounted on said shaft, a one way clutch mounted on said shaft and arranged to connect said worm with said shaft when the latter moves 125 in a reverse direction, a shaft extending at right angles to said operating shaft, a worm mounted on the last mentioned shaft and meshing with and rotatable by said worm wheel, a second worm wheel mounted on 130

- 5 said shaft and rigidly connected with said worm, a shaft extending parallel with said operating shaft, a second worm mounted on said shaft and meshing with and rotatable by said second worm wheel, a brake member secured to the last mentioned shaft, friction devices coöperating with said brake member, and manually controlled means for manipulating said friction members.
- 10 6. In a lifting jack, a lifting member, a worm wheel, means to connect said worm wheel with said lifting member when the latter moves downwardly, a worm meshing with and rotatable by said worm wheel, braking devices to control the rotation of said worm and comprising a friction drum, a pair of intersecting arms mounted adjacent to said friction drum, brake shoes carried by the respective arms, and arranged 15 to engage said friction drum, a spring acting on said arms to move said brake shoes into engagement with said friction drum, a cam to move said arms one from the other against the tension of said spring, and a lever connected with said cam.
- 20 7. In a lifting jack a lifting member, a pair of intermeshing members to retard the downward movement of said lifting member, means to connect one of said retarding members with said lifting member when the latter moves downwardly, a braking device connected with the other retarding member, said retarding members having their intermeshing parts arranged spirally 25 of their respective circumferences and also having said intermeshing parts so arranged that the last mentioned retarding member will be rotated by the first mentioned retarding member and a second pair of retarding devices interposed between the first 30 mentioned retarding device and said braking device and having intermeshing parts arranged spirally of their respective circumferences and serving both to absorb power 35 and to accelerate the speed of the mechanism at the braking device, and to thereby facilitate the control of said mechanism by said braking device, a casing inclosing both pairs of retarding devices and adapted to contain a lubricant, said braking device being arranged exteriorly of said casing.
- 40 8. In a lifting jack, a lifting member, a pair of intermeshing members to retard the downward movement of said lifting member, means to connect one of said retarding members with said lifting member when the latter moves downwardly, and a braking device 45 interposed with the other retarding member, said retarding members having their intermeshing parts arranged spirally of their respective circumferences, and also having said intermeshing parts so arranged that the last mentioned retarding member will be rotated by the first mentioned retarding member, and means interposed between said last mentioned retarding member and said braking device to further absorb the power transmitted to said retarding members by said lifting member.
- 50 9. In a lifting jack, a lifting member, a worm wheel, means to connect said worm wheel with said lifting member when the latter moves downwardly, a worm meshing with and rotated by said worm wheel, a braking device, and means interposed between said worm and said braking device to further absorb the power transmitted to said worm by said worm wheel.
- 55 10. In a lifting jack, a lifting member, a pair of intermeshing members to retard the downward movement of said lifting member, means to connect one of said retarding members with said lifting member when the latter moves downwardly, a worm meshing with and rotated by said worm wheel, a braking device connected with the other retarding member, said retarding members having their intermeshing parts arranged spirally of their respective circumferences and also having said intermeshing parts so arranged that the last mentioned retarding member will be rotated by the first mentioned retarding member, and a second pair of retarding devices interposed between the first mentioned retarding device and said braking device and having intermeshing parts arranged spirally of their respective circumferences, and serving both to absorb power and to accelerate the speed of the mechanism at the braking device and to thereby facilitate the control of said mechanism by said braking device, a casing inclosing both pairs of retarding devices and adapted to contain a lubricant, said braking device being arranged exteriorly of said casing.
- 60 11. In a lifting jack, a lifting member, a worm wheel, a clutch to connect said worm wheel with said lifting member when the latter moves downwardly, a worm meshing with and rotated by said worm wheel, a braking device, means interposed between said worm and said braking device to absorb the power transmitted from said worm to said worm wheel, and a housing adapted to contain a lubricant in which one or more of said parts is wholly, or partially, immersed.
- 65 12. In a lifting jack, a lifting member, a shaft operatively connected with said lifting member, a worm wheel mounted on said shaft and adapted to be rotated thereby when said shaft is rotated by the downward movement of said lifting member, a worm meshing with said worm wheel and having its spiral so arranged that said worm will be rotated by said worm wheel, means for controlling the rotation of said worm, and a housing inclosing said worm and worm wheel and adapted to contain a lubricant in which one or both of said parts operate.
- 70 13. In a lifting jack, a rotatable actuating

member, a shaft having geared connection with said actuating member, an operating device connected with said shaft to impart lifting movement to said actuating member,
5 a device arranged adjacent to said operating device and connected with said rotatable actuating member to retard the downward

movement thereof, and means for controlling said retarding device.

In testimony whereof, we affix our signatures hereto.

CHARLES W. RIPSCH.
JAMES C. DAWLEY.
